UNITED STATES PATENT OFFICE.

HOWARD G. WIDMER, OF BROOKLYN, NEW YORK, ASSIGNOR TO ARKELL SAFETY BAG COMPANY, OF NEW YORK, N. Y., A CORPORATION OF NEW YORK.

MACHINE FOR MAKING CRINKLED PAPER.

Application filed January 9, 1919. Serial No. 270,270.

This invention relates to improvements in machines for making crinkled paper. The invention seeks to provide simple, convenient and efficient means for applying pressure to the paper immediately in advance of the doctor or abutment that forms the crinkles in the paper whereby the paper may be more uniformly crinkled, especially along its margins, and finer, closer and more numerous crinkles may be formed in the paper, especially in the heavier papers adapted for wrapping and packing purposes.

The invention consists of the features hereinafter pointed out.

15 In the accompanying drawings forming part of this specification and in which like reference numerals designate corresponding parts, the invention is illustrated in its preferred form. In these drawings,

20 Fig. 1 is a side elevation, partly in section, of a crinkling machine to which the paper is applied.

Fig. 2 is a front elevation looking toward the left of Fig. 1 and partly broken away.

25 Referring now to the particular structure shown in the drawing, 1 is a rotating crinkling cylinder providing a supporting surface for the paper 2 which is deposited on the cylinder by the guide roll 3. As the paper 30 is carried forward on the cylinder it meets an abutment 4, generally called a doctor, which is held in contact with the surface of the cylinder. The paper is stripped from the cylinder by this abutment and is thereby formed into crinkles. The doctor or abutment 4 provides crinkle-forming means which act to crinkle the paper and also to strip the paper from the cylinder or supporting surface. Such crinkle forming 40 means may be variously constructed and arranged but is preferably a stationary element. 5 is that portion of the paper in which the crinkles have been formed and which is shown in the drawings as being carried away on the endless carrier 6 supported at one end by the roll 6¹. Before the paper 45 meets the abutment 4 it is moistened by suitable means, generally by being carried through one or more tanks containing water.

50 As shown in the drawings, the cylinder 1 with the paper thereon rotates in a tank 7 containing water. 8 is a roll bearing against the paper on the cylinder after the paper has left the tank 7. This roll 8 serves to press 55 the paper in close contact with the cylinder,

smoothing it thereon, and also serves to squeeze out any surplus moisture in the paper.

In order that the paper may be held on the cylinder to assist the abutment 4 in carrying out its function, a presser piece 9 is arranged to apply pressure to the paper immediately in advance of the operating edge of the abutment 4. As shown in the drawings, this presser piece in its preferred arrangement is in the form of a blade or bar and is best made of metal having a smooth operating surface to eliminate friction so far as possible. It extends axially across the cylinder 1 with its forward edge in close proximity to the operating edge of the doctor. Since it preferably contacts with the paper throughout its width, to impose a restraint upon the paper it acts to resist or limit the stripping action of the doctor upon the paper because the paper cannot leave the cylinder or be stripped therefrom back of the forward edge of the presser piece. By the use of this presser piece the crinkles in the paper may be made finer, closer together and more numerous and the paper may be more uniformly crinkled throughout its width than has heretofore been practicable in crinkling machines now in actual use. In particular the present invention operates to obviate the uncrinkled spots that show along the margins of the paper as heretofore crinkled. This is especially true with respect to the heavier grades of paper suitable for wrapping or packing purposes. The closer to the operating edge of the doctor that the presser piece applies its pressure on the paper the finer, closer and more numerous will be the crinkles in the paper.

In the preferred arrangement of the presser piece, it is provided with a rigid backing consisting of a metal bar 10 whose opposite ends are secured by screws 11 and 12 to levers 13 and 14. The lower ends of these levers are pivotally mounted on trunnions 15 and 16 provided on the ends of arbors 17 and 18 whose flattened portions enter slots 19 and 20 in brackets 21 and 22 fixed on the frame of the machine. Each of the arbors 17 and 18 has a circular shoulder 105 as 23 bearing against the inner face of its carrying bracket and also has its outer end threaded to receive a clamping nut as 24. By these means these arbors 17 and 18 may be adjusted vertically to widen or narrow 110

the space between the presser piece and the doctor. The lower ends of the levers 13 and 14 are bent as shown in Fig. 1 to bring the upper ends of these levers to an angle of about 45° to the horizontal and their upper ends are provided with adjustable weights 25 and 26. It will thus be seen that the presser piece bears with a yielding pressure against the paper and this pressure may be varied by shifting the weights 25 and 26 up or down on their levers. The means for thus mounting the presser piece may, of course, be varied without departing from the scope of the invention and the form and the arrangement of the presser piece itself may be likewise varied.

What I claim is:

1. In a machine for making crinkled paper, a supporting surface for the paper and crinkle-forming means acting to strip the paper from said surface and crinkle it, in combination with a presser piece for applying pressure to the paper immediately in advance of said crinkle-forming means to limit the stripping action thereof.

2. In a machine for making crinkled paper, a supporting surface for the paper and crinkle-forming means acting to strip the paper from said surface and crinkle it, in combination with a presser piece for applying pressure to the paper immediately in advance of said crinkle-forming means to limit the stripping action thereof, and means for varying the distance between said crinkle-forming means and presser piece.

3. In a machine for making crinkled paper, a supporting surface for the paper and crinkle-forming means acting to strip the paper from said surface and crinkle it, in combination with a presser piece for applying pressure to the paper immediately in advance of said crinkle-forming means to limit the stripping action thereof, and means for varying the pressure of the presser piece.

4. In a machine for making crinkled paper, a supporting surface for the paper and crinkle forming means to strip the paper from said surface and crinkle it, in combination with a presser piece for applying pressure to the paper immediately in advance of the crinkle forming means, means for varying the distance between said crinkle forming means and presser piece, and means for varying the pressure of the presser piece.

5. In a machine for making crinkled paper, a supporting surface for the paper and crinkle-forming means acting to strip the paper from said surface and crinkle it, in combination with a yielding presser piece for applying yielding pressure to the paper immediately in advance of said crinkle-forming means to limit the stripping action thereof.

6. In a machine for making crinkled paper, a supporting surface for the paper and crinkle-forming means acting to strip the paper from said surface and crinkle it, in combination with a yielding presser piece for applying yielding pressure to the paper immediately in advance of said crinkle-forming means to limit the stripping action thereof, and means for varying the pressure of the presser piece.

7. In a machine for making crinkled paper, a supporting surface for the paper and crinkle forming means to strip the paper from said surface and crinkle it, in combination with a yielding presser piece for applying yielding pressure to the paper immediately in advance of the crinkle forming means, means for varying the distance between said crinkle forming means and presser piece, and means for varying the pressure of the presser piece.

8. In a machine for making crinkled paper, a supporting surface for the paper and crinkle forming means to strip the paper from said surface and crinkle it, in combination with a presser piece consisting of a pivotally mounted stationary bar for applying pressure to the paper immediately in advance of the crinkle forming means.

9. In a machine for making crinkled paper, a supporting surface for the paper and crinkle forming means to strip the paper from said surface and crinkle it, in combination with a presser piece consisting of a pivotally mounted stationary bar for applying pressure to the paper immediately in advance of the crinkle forming means, and means for varying the distance between said crinkle forming means and presser piece.

10. In a machine for making crinkled paper, a supporting surface for the paper and crinkle forming means to strip the paper from said surface and crinkle it, in combination with a yielding presser piece consisting of a pivotally mounted stationary bar for applying yielding pressure to the paper immediately in advance of said crinkle forming means.

11. In a machine for making crinkled paper, a supporting surface for the paper and crinkle forming means to strip the paper from said surface and crinkle it, in combination with a yielding presser piece consisting of a pivotally mounted stationary bar for applying yielding pressure to the paper immediately in advance of said crinkle forming means, and means for varying the distance between said crinkle forming means and presser piece.

12. In a machine for making crinkled paper, the combination with a crinkling cylinder and crinkle forming means to strip the paper from said cylinder and crinkle it, of a pair of pivotally mounted levers carried on

the machine and a presser piece carried by said levers and adapted to bear on the paper carried by said cylinder immediately in advance of said crinkle forming means.

5 13. In a machine for making crinkled paper, the combination with a crinkling cylinder and crinkle forming means to strip the paper from said cylinder and crinkle it, of a pair of pivotally mounted levers carried on

10 the machine and a presser piece carried by said levers and adapted to bear on the paper carried by said cylinder immediately in advance of said crinkle means, and provisions for varying the distance between said presser piece and said crinkle forming means.

15 14. The combination with a crinkling cylinder and crinkle forming means to strip a web of paper from the cylinder and to thereby crinkle it, of a mechanical member immediately in advance of said crinkle forming means to limit the stripping action thereof.

20 15. The combination with a crinkling cylinder and crinkle forming means to strip a web of paper from the cylinder and to thereby crinkle it, of a mechanical member immediately in advance of said crinkle forming means to hold the paper on the cylinder against the stripping action thereof.

25 16. The combination with a crinkling cylinder and crinkle forming means to strip a web of paper from the cylinder and to thereby crinkle it, of an adjustable mechanical

member immediately in advance of said crinkle forming means to limit the stripping action thereof.

35

17. In combination, a crinkling cylinder, a squeeze roll to press a web of paper against the crinkling cylinder, crinkle forming means to strip the paper from the cylinder and crinkle it, and mechanical means intermediate the squeeze roll and said crinkle forming means to impose restraint upon the paper and limit the stripping action thereof.

40

18. In combination, a crinkling cylinder, a squeeze roll to press a web of paper against the crinkling cylinder, crinkle forming means to strip the paper from the cylinder and crinkle it, and an adjustable mechanical means intermediate the squeeze roll and said crinkle forming means to impose restraint 45 upon the paper and limit the stripping action thereof.

50

19. In an apparatus for making crinkled paper, means for wetting the paper, a crinkling cylinder to receive the wet paper, a squeeze roll to press the paper against said cylinder, and an abutment to strip the wet paper from the cylinder and thereby crinkle it, in combination with a mechanical member immediately in advance of the abutment 55 to limit the stripping action thereof.

60

This specification signed this 8th day of January, 1919.

HOWARD G. WIDMER.
